UNITED STATES PATENT OFFICE.

WILLIS A. GIBBONS, OF FLUSHING, NEW YORK, ASSIGNOR TO RUBBER REGENERATING COMPANY, A CORPORATION OF INDIANA.

PNEUMATIC CUSHION.

1,321,301.

Specification of Letters Patent. Patented Nov. 11, 1919.

Application filed May 10, 1916. Serial No. 96,508.

To all whom it may concern:

Be it known that I, WILLIS A. GIBBONS, a citizen of the United States, residing at Flushing, L. I., county of Queens, State of New York, have invented certain new and useful Improvements in Pneumatic Cushions, of which the following is a full, clear, and exact description.

This invention relates to pneumatic cushions and has for an object to provide a chair, automobile or other cushion, which is self filled with air at atmospheric pressure, and which retains this air under increased pressure when in use.

Pneumatic cushions as ordinarily constructed require frequent pumping to keep them properly inflated. To obviate inflating by pumps, the present invention provides a cushion which fills itself with air at atmospheric pressure when not in use, this air being imprisoned and its pressure increased when the cushion is in use.

With the above and other objects in view, the invention consists in certain novel details of construction and combinations of parts hereinafter fully described and claimed, it being understood that various modifications may be resorted to within the scope of the appended claims.

The invention can be readily understood from the following description taken in connection with the accompanying drawing, in which—

Figure 1 is a cross-sectional view showing a cushion embodying my improvements, when not in use.

Fig. 2 is a view similar to Fig. 1 showing the cushion in use.

Fig. 3 is a view similar to Fig. 2 showing the cushion in the act of inflating itself after loss of air.

Fig. 4 is a plan view of the cushion with the top thereof removed.

Fig. 5 is a fragmentary sectional view showing the manner of attaching the spring to the frame of the cushion.

Referring now to the drawing in which like characters of reference designate similar parts, a cushion is shown comprising a bottom 10, a top 11, and side walls 12, which form a substantially air tight inclosure or envelop. An arched leaf spring 13 is terminally supported upon the bottom 10 and centrally abuts the top 11 of the cushion.

An opening 14 formed in the bottom 10 es-

tablishes communication between the interior of the cushion and the exterior atmosphere, and passage of air through this opening is controlled by a check valve 15.

In operation the spring 13 causes the top 60 and bottom of the cushion to move apart and act as a bellows, which draws air in through the check valve 15 until the pressure of air within the cushion reaches atmospheric pressure. When the cushion is in use the 65 weight of the user compresses the air within the cushion, thereby closing and maintaining the check valve closed to prevent the escape of air. The air thus imprisoned within the cushion is compressed in proportion to 70 the weight of the user to afford suitable buoyancy. Such air as leaks through the valves, seams or walls of the cushion will be replaced through the check valve during 75 expansion of the cushion under the influence of the spring when the user rises.

In the present embodiment I have shown the side walls of the cushion as flexible and reinforced at the top and bottom edges by frames 16 and 17, which are yieldingly held 80 spaced apart by leaf springs 18 near the corners. These frames and leaf springs operate to maintain the shape of the cushion as well as adding rigidity to prevent collapse thereof under excessive load. Furthermore, 85 I have shown the ends of the operating spring 13 looped around the bottom frame 17 to prevent spreading apart of the ends and to present rounded surfaces which will not mutilate the bottom. Cylindrical rubber 90 bumpers 19 are secured to the spring and act as a cushion underneath the ends of the spring when the latter is depressed to an excessive extent. I have also shown the bottom of the cushion as stiffened by a fiber 95 board sheet 20 which may be cemented or otherwise secured to the bottom and reinforces the same against warping or other distortion.

Under some conditions of service it may 100 be necessary to dispense with the above described check valve which acts under a slight pressure difference, and employ instead a valve such as is used in bicycle tires, the same to be opened by pressing in the plunger 105 when it is necessary to inflate the cushion.

In either case, whether the valve employed is self acting under slight pressure difference, or must be opened by hand, the cushion is a self inflating cushion which itself pro- 110

vides the means for obtaining the necessary difference in pressure between the interior of the cushion and the exterior atmosphere, the actual means for entrance of air and equalization of this pressure being the check valve operated by said pressure difference, or any other type of valve operated by hand or some mechanical means.

The above described parts of the cushion 10 such as the top, bottom and side walls may be of any desired material and the cushion as such may be inclosed within an outer protective covering if desired. Furthermore, any desired type of spring may be 15 used, and in fact, other means than a spring may be used to expand the cushion.

Having thus described my invention, what I claim as new and desire to protect by Letters Patent is:

20 1. A self-inflating cushion, embodying a casing having a yielding wall, said casing being sufficiently impervious to the passage of air to support the load resting upon the cushion, means for automatically expanding

the casing when the load is removed, means 25 for automatically admitting air to the casing when the load is removed, a pair of frames disposed within said casing, and yielding means for normally holding said frames in spaced relationship.

2. A self-inflating cushion embodying a casing having a yielding wall, said casing being sufficiently impervious to the passage of air to support the load resting upon the cushion, a pair of frames confined within 35 said casing, yielding means for normally holding said frames in spaced relationship, a bow spring having its ends secured to one of said frames and arranged to automatically expand the casing when the load is removed, rubber bumpers adapted to cushion the bow spring when said spring is in a depressed position, and means for automatically admitting air to the casing when the load is removed.

Signed at New York, N. Y., this 6th day of May, 1916.

WILLIS A. GIBBONS.
